UNITED STATES PATENT OFFICE.

WINFIELD SCOTT PROSKEY, OF RENO, NEVADA, ASSIGNOR OF ONE-HALF TO WILLIAM DULLES, OF ENGLEWOOD, NEW JERSEY.

RUNNING-GEAR FOR VEHICLES.

1,319,244.

Specification of Letters Patent.

Patented Oct. 21, 1919.

Application filed October 15, 1914. Serial No. 866,749.

To all whom it may concern:

Be it known that I, WINFIELD SCOTT PROSKEY, a citizen of the United States, residing at Reno, in the county of Washoe 5 and State of Nevada, have invented certain new and useful Improvements in Running-Gears for Vehicles, of which the following is a full, clear, and exact description.

The invention which forms the subject of 10 the present application relates to running gear for vehicles, chiefly with the object of improving the "riding qualities" thereof. To this and other ends the invention consists in the novel features of construction and combinations of elements hereinafter 15 described.

Several embodiments of the invention are illustrated in the accompanying drawing. These are illustrated somewhat diagrammatically, no attempt being made to indicate with any degree of exactness the relative proportions of such parts as depend for 20 their design upon the varying conditions of use. Matters of that kind are best left to the skill of the engineer or designer in applying the invention in practice.

Referring now to the drawing, Figure 1 shows in side elevation the preferred form of the invention, and Fig. 2 shows a modification of this form. Fig. 3 shows another 25 embodiment.

Throughout the drawing, the part designated by 10 may be taken to represent part of the vehicle body, or its supporting frame, as for example one of the longitudinal side-members of a chassis. The body or frame is supported on each end of the axle (shown in section at 11) by means of a toggle-like construction consisting of two links 12, 13, 30 extending toward the front and rear, respectively, and pivotally connected together at their inner ends through the medium of a fulcrum member 14 rigidly secured to the axle.

In Fig. 1 the outer ends of the toggle 45 members 12, 13 are pivotally connected to the frame member 10 by vertical levers or links 15, 16, which are slotted vertically between their ends to receive the pins 17, 18 connecting them with the horizontal rods 19, 20. These latter are connected to suitable resilient or yielding devices, as for example the coil springs 21, 22, bearing at 50 their inner ends on abutments 23, 24, fixed to the member 10, and at their outer ends

on stop disks or plates 25, 26 on the rods 55 19, 20. These stops rest against nuts on the threaded ends of the rods, by which the tension of the springs can be regulated. The abutments or stops 23, 24 are provided with apertures, not shown, through which 60 the rods pass.

The operation will now be readily understood. As the vehicle travels the vertical movement of the axle relative to the frame 10, due to irregularities of the roadway, 65 "straightens" the toggle, more or less, against the tension of one or both of the springs 21. On the other hand, downward movement of the axle relative to the vehicle frame or body "buckles" the toggle against the tension of one or both of the springs 22. In each case the vertical movement of the axle is, through the medium of the toggle and the levers 15, 16, exerted on the springs in a horizontal direction longitudinally of the 70 vehicle.

The construction in Fig. 2 differs but slightly from that shown in Fig. 1, the links or levers 15^a, 16^a, in Fig. 2, being connected to the horizontal rods at the ends of the latter instead of at intermediate points. The 80 operation is of course the same as in Fig. 1.

In Fig. 3 the abutments 23^a, 24^a are pivotally connected to the frame 10 instead of rigidly. For this purpose the abutments are 85 carried by body members 27, which are pivoted on brackets 28, 29 depending from the frame 10. Moreover, the rods 19^a, 20^a, corresponding to the rods 19, 20, in Fig. 1, are in line with and connected rigidly to the 90 toggle links 12, 13,—in fact form part of these links. The operation is essentially the same as that of the structures illustrated in Figs. 1 and 2.

In Figs. 1 and 2 the toggle links are of 95 the telescopic type to provide for such variation of length as may be necessary or desirable, the two parts of each link being locked together after adjustment by means of binding sleeves 30. In Fig. 3 a similar 100 adjustment is obtained by screwing the rods 19^a, 20^a in or out of the members 12, 13.

I prefer to have the toggles and springs arranged longitudinally of the vehicle, but the transverse arrangement is sometimes desirable. This condition can be illustrated by merely turning the drawing upside down, in which case the part 10 will represent the 105

axle, with the wheel spindles omitted, while the part 11 will represent the vehicle body or a longitudinal element of the body frame.

It is to be understood that the invention 5 is not limited to the constructions herein specifically illustrated but can be embodied in other forms without departure from its spirit.

I claim:

- 10 1. In a running gear, the combination with a vehicle body and an axle, of forwardly and rearwardly extending members pivotally connected at their inner ends to the axle and at their outer ends to links, 15 said links being pivoted at their upper ends to the body, yielding means coöperating with the links and acting intermediate the pivots thereof for horizontal movement of the outer ends of said members, and means 20 for varying the length of the forwardly and rearwardly extending members.
2. In a running gear, the combination with a vehicle body and an axle, of forwardly and rearwardly extending members 25 pivotally connected at their inner ends to the axle, vertical links pivotally connecting the outer ends of the members to the body, means associated with the aforesaid members for adjusting the position of the axle 30 with respect to the body, and yielding devices coöperating with the said links and act-

ing intermediate the pivots thereof adapted to cushion or resist pivotal movement thereof.

3. In a running gear, the combination 35 with a vehicle body and an axle; of toggle mechanism between the body and the axle, comprising longitudinally adjustable oppositely extending members pivotally connected together at their inner ends, and vertical 40 links pivoted to the outer ends of the members and the body; and yielding means co-operating with the links and acting intermediate the pivots thereof and adapted to cushion or resist pivotal movement thereof. 45

4. In a running gear, the combination with a vehicle body and an axle, of a telescopic toggle connected to the axle and extending forwardly and rearwardly therefrom, vertical links pivotally connected to 50 the body and the front and rear ends of the toggle, and horizontally acting helical springs connected with the links intermediate the pivots thereof and adapted to cushion or resist forward and rearward pivotal movement of the links. 55

In testimony whereof I affix my signature in the presence of two subscribing witnesses.

WINFIELD SCOTT PROSKEY.
